UNITED STATES PATENT OFFICE

JACOB E. ECKSTEIN, OF PITTSBURGH, PENNSYLVANIA

FOUNTAIN BRUSH

Application filed March 27, 1931. Serial No. 525,645.

This invention relates to fountain brushes, and its objects are to provide such brushes with means for holding a supply of material to be used with the brush, and for feeding it to the bristles, which is of simple and inexpensive construction, sturdy, of easy and efficient operation, and is generally an improvement over prior types of such devices.

The invention is applicable to any type of brush adapted to fountain type construction, i. e. which may operate with a cleaning, polishing, or the like material in paste or plastic form. However, for purposes of explanation it may be described in connection with the accompanying drawing which illustrates its application to a shoe brush. Fig. 1 shows a longitudinal cross section through the preferred embodiment of the invention as applied to a shoe brush; and Fig. 2 an enlarged fragmentary view of a portion of the device shown in Fig. 1; and Fig. 3 a cross section taken on line III—III, Fig. 1.

The device provided by this invention comprises a casing member connected to the bristle-supporting head of a brush on the side opposite the bristles. The casing surrounds one end of a bore extending through the head to the bristles, and it is shaped to hold a tube containing material to be supplied to the bristles and having one end adapted to project into and make a snug fit with the bore. The device is also provided with means for expelling the material from the tube, and by virtue of this construction the material passes directly to the bristles.

Having reference now to the illustrative embodiment shown in the drawing, a brush is conventionally represented as having a head 1 provided with bristles 2 which project from the lower side thereof. This head may assume any of a variety of forms, depending upon the use to which the brush is to be put. The form shown is adapted to be used as a dauber for shoe polish, but the shape and construction of the brush may be modified to adapt it to other uses, such as for shaving brushes, and the like.

The head is provided with a bore 3 adapted to receive the tip of a tube 4 disposed within a casing 5 connected to the upper side of the

head. The tube contains a material 6, such as shoe polish, which is to be supplied to the bristles, and which is in the form of a cream, paste or the like. In the preferred embodiment this tube is formed from rigid material adapted to resist distortion, and it is of substantially uniform cylindrical cross section from its upper end to a point adjacent its lower end. The lower end of the tube is shaped to conform to and make a snug fit with bore 3. Preferably bore 3 tapers downwardly and inwardly from the upper side of the head, and the lower end of the tube is correspondingly tapered to project into the bore in the manner described, and as shown particularly in Fig. 2. The bore is preferably disposed centrally of the head, as shown in the drawing, although it may be placed otherwise, as where it is desirable to feed material near one side of the bristles.

The contents of tube 4 are expelled to the bristles by any suitable means. In the preferred embodiment such means take the form of a plunger movable longitudinally in the tube and actuated positively by fixed position screw mechanism. Various forms of such expelling means are known. The form shown comprises a plunger 8 mounted above the material in the upper end of tube 4. This plunger makes a snug fit with the tube, and its shape corresponds to that of the lower end of the tube, so as to expel all of its contents.

Actuation of the plunger is effected by means of a threaded shaft 9 which moves in similar threads formed in a central longitudinal bore in plunger 8. The shaft extends downwardly through the tube, and its upper end is provided with a head 10. Shaft 8 is held in the tube by a cap 11 connected to casing 5, a lock washer 12 connected to the shaft beneath the cap preventing the shaft from moving outwardly when rotated.

Rotation of plunger 8 may be prevented in various ways. For example, tube 4 may be provided interiorly with one, preferably two, longitudinal ribs 13 which act as guides for similar grooves 15 formed in the plunger. This construction is seen best in Fig. 3. Positive actuation of plunger 8 is thus provided. Upon rotation of shaft 9 by means of head

10 the plunger will be moved downwardly into the tube. This applies pressure to the material and forces it through the tip to the bristles, the amount thus fed being dependent, of course, on the travel of the plunger.

Fig. 1 shows the device as combined with a shoe brush having a back 16 provided with any suitable polishing means, such as bristles 17. The device provided by the invention is connected to back 16 in any desired manner. For example, as shown in the drawing it extends along the back and is connected thereto by straps 18. As here shown the device provides means for applying polish to a dauber. To this end tube 4 contains shoe polish in paste or cream form, and bristles 2 are supplied with it in the manner described. The invention is applicable equally to other types of fountain brush. For example, the head of shaving brushes may be provided with this means for applying shaving cream. In such an application the device replaces the customary brush handle. Other similar applications will be understood by those skilled in the art.

The brush provided by this invention is of simple construction. The tube fits directly into the bristle head, and the bore forms a conduit for passing its contents directly to the bristles. This eliminates the use of nipples and similar connections between the tube and the bristles which have characterized fountain brushes prior to my invention. Such connecting members have been disadvantageous. Thus, they are damaged readily, and they usually are connected to the tube by screw threads. Such connections are not made readily, and the ends of both the tubes and the nipples are easily bent or damaged.

40 This hinders or prevents connection between the tube and the nipple, and may render such devices useless. Furthermore, such connections may become clogged easily, as by hardening of the material in the relatively small bore passage thus provided.

In the brushes provided by this invention the tip of the tube is pushed into the aperture formed in the bristle head and makes a snug seat therewith. There are no connections to become damaged or requiring threaded engagement, and the material in the tube is thus expelled directly to the bristles. By virtue of this construction also it is easy to insert fresh tubes, for the tube end is readily inserted into the bore, after which it finds a proper and snug seat therein. This constitutes a major advantage of my invention over the devices used heretofore.

60 The tubes, being rigid, resist distortion, both before being inserted in the brush, and in use. The previously used small tubular outlets are dispensed with, while the form shown seeks the bore in the head and the pressure applied by the plunger causes the tube to always seat snugly in the bore. Not only

does this render assembly easy, but also it prevents leakage.

The aperture through the bristle head and the shape of the lower end of the tube may, however, assume forms other than that shown, the gist of this being the combination of a tube tip fitted directly into a bore formed in the brush head. In the tapered forms of tip the space between the lower end of the tube and head 1 may be filled by a 70 backing member 19, Fig. 2, conforming generally to the shape of the tube end. The heads of the brushes are preferably provided with means for closing the bore when the brush is not in use. This prevents drying of 75 the material in the tube. For example, a gate 20 is slidably mounted in head 2. When pushed in it closes bore 3, and upon being pulled out material 6 may be supplied to the bristles.

85 When the contents of a tube have been wholly expelled cap 11 and the screw mechanism are removed. The plunger then may be inserted in a fresh tube placed in the casing, and the shaft screwed into place. For 90 most purposes, however, it is preferred to supply the tubes with the plungers in place. In such a case it is necessary only to insert the shaft and set cap 10 in place, when the brush is again ready for use.

95 According to the provisions of the patent statutes, I have explained the principle and mode of operation of my invention and have illustrated and described what I now consider to represent its best embodiment. However, 100 I desire to have it understood that, within the scope of the appended claims, the invention may be practiced otherwise than as specifically illustrated and described.

105 I claim:

1. A fountain brush comprising in combination a head, bristles mounted in and projecting from one side of said head, a tubular casing connected to the other side of the head surrounding one end of a bore of varying cross-section extending through the head, a tube containing material to be supplied to the bristles disposed in said casing with its lower open end projecting slidably into and slidably snugly fitting said bore within the head for expulsion of said material to the bristles; and means for feeding material in desired amounts from the tube directly to the bristles.

110 2. A fountain brush comprising in combination a head provided centrally with a bore extending through and tapering downwardly and inwardly from the upper to the lower side of the head, bristles projecting from the lower side of the head, a casing surrounding the upper side of said bore, a rigid cylindrical tube containing material to be supplied to the bristles having its lower end tapered to fit said bore disposed in said casing with its lower end projecting slidably into and slid-

ably snugly fitting the bore, and a plunger movable longitudinally in said tube for expelling said material from the tube directly to the bristles.

5. In a fountain brush, the combination of a head provided with a bore tapering inwardly and downwardly from the upper to the lower side of the head, bristles projecting from the lower side of the head, a tubular casing surrounding the upper end of said bore on the side opposite said bristles, a cylindrical tube formed from rigid material disposed in said casing and having its lower open end tapered and projecting slidably into and slidably snugly fitting said bore, said tube containing a material to be supplied to the bristles, a movable plunger mounted in said tube above said material, and means for moving said plunger downwardly into said tube to expel said material, said means including a threaded shaft passed through and co-acting with threads formed in said plunger to positively move the plunger longitudinally of the tube when the shaft is rotated.

25. 4. A fountain brush comprising the combination of a head provided with bristles projecting from one side thereof and with a centrally disposed bore sloping downwardly and inwardly from the side opposite said bristles, 30 a tubular casing surrounding the end of said bore on the side opposite said bristles, a cylindrical tube formed from rigid material disposed in said casing and having its lower end projecting slidably into and slidably 35 snugly fitting the bore, the tube being provided with a longitudinal interior rib and containing material to be supplied to said bristles, a grooved plunger disposed in said tube above said material with its groove engaging said rib, a threaded bore in said plunger, and a threaded shaft engaging said threaded bore and extending downwardly substantially to the lower end of said tube, rotation of said shaft positively moving said 40 plunger into said tube and expelling said material to the bristles.

45. 5. A brush according to claim 2, said plunger being tapered to correspond to the taper of the lower end of said tube, whereby 50 to effect substantially complete expulsion of the tube contents.

In testimony whereof, I sign my name.
JACOB E. ECKSTEIN.
